*Louise Ludwig Inventor
By his Attorney Frank A. Hart*

UNITED STATES PATENT OFFICE

LOUIS LUDWIG, OF BROOKLYN, NEW YORK

SOCKET FOR ELECTRIC LAMPS

Application filed September 14, 1926. Serial No. 135,303.

This invention relates to a socket for electric lamps and has for its object the provision of a compact socket containing a thermostatic circuit controller so that by the use of this socket a blinking electric light can be used wherever current is available. Further objects and advantages of the invention will become apparent as the description proceeds.

While a preferred embodiment of the invention has been disclosed for purposes of illustration, it should be understood that various changes may be made in the structure without departing from the spirit and scope of the invention as hereinafter set forth and claimed.

In the drawings:

Fig. 1 is a horizontal section through a socket embodying the invention;

Fig. 2 is a cross section on line 2—2 of Fig. 1;

Fig. 3 is a section on line 3—3 of Fig. 4;

Fig. 4 is an elevation of the thermostatic unit.

Referring more specifically to the drawings, the socket comprises the tubular metallic shell 10 the lower end of which is threaded as at 11 to cooperate with a conventional socket, while the upper end is threaded at 12 to receive a lamp. A partition disc 13 of insulating material extends across the middle of the shell, and forms the bottom of the lamp-receiving socket.

The thermostatic unit is supported on a base 14 of mica or other insulating material. The thermostatic arm 15 is of a well-known construction and is spaced from the base 14 by a metallic bushing 16, a screw bolt 17 holding the arm in place. The upper end of the thermostatic arm carries the contact point 18 adapted for cooperation with the contact screw 19 adjustably mounted on the base 14.

The lower end of the tubular shell 10 is closed by a core 20 of insulating material through which is formed a tapered aperture 21. The lower end of the thermostatic unit projects into the aperture 21 and is held in position by the conducting wires. The wire 22 is clamped under the bushing 16 and has its ends sealed in a plug of solder 23 closing the end of aperture 21. The upper wire 24 is

held under one of the units securing the contact screw 19 and is sealed in the plug of solder 25 extending through the disc 13 and forming the central contact for a lamp screwed into the socket. In this manner the thermostatic element is freely suspended in an insulated position in such a manner that it cannot contact with the side walls of the shell.

The thermostatic arm is surrounded by a coil 26 of fine wire in a well-known manner, the lower end of the coil being connected to screw bolt 17 and its upper end being connected to contact screw 19. The side of shell 10 is apertured as at 27 to permit circulation of air so that the thermostatic arm can cool to break contact in the well-known manner. A sleeve 28 of insulating material surrounds the upper end of the shell.

It will be understood that when the parts are in the position of Fig. 1 current passes to the lamp through coil 26, and due to the resistance of the coil only a small amount of current passes to the lamp and the lamp does not glow. At the same time the heating of the coil causes the thermostatic arm to bend until it makes contact with the screw 19. At this time the current passes directly through the arm 15 and the lamp becomes illuminated while the coil cools and finally the arm 15 breaks the contact and returns to the starting position.

The structure set forth comprises a simple and inexpensive socket including a thermostatic circuit-breaking mechanism and is adapted to produce a blinking light heretofore obtained by more complicated and expensive apparatus.

I claim:

A thermostatic circuit controller for insertion in a conventional lamp socket and comprising a base of insulating material, a conductive binding post mounted at one end of the base, a thermostat arm carried by said post and extending normally parallel to the base, said arm having a winding of resistance wire and carrying a contact at its free end, a screw extending through the base in alignment with said contact, said screw being elec-

100

trically connected to the resistance wiring of the arm, and nuts on said screw on opposite sides of the base holding the screw in adjusted position, one of the nuts forming a binding nut for a lead wire.

5 In testimony whereof I affix my signature.

LOUIS LUDWIG.
